CLAIM

I claim the ornamental design for a truck bed tie down cleat, substantially as shown and described.

DESCRIPTION

FIG. 1 is a top, front, left side perspective view showing my new design of a truck bed tie down cleat;

FIG. 2 is a top view thereof, the bottom view being identical thereof;

FIG. 3 is a left side view thereof, the right side view being identical thereof;

FIG. 4 is a front view thereof; and,

FIG. 5 is a rear view thereof.

The broken lines shown in the drawings depict portions of the truck bed tie down cleat that form no part of the claimed design.
